UNITED STATES PATENT OFFICE.

HERMAN L. GREVE, OF NEW YORK, N. Y.

CORDAGE WRAPPER AND PACKAGE.

Application filed June 2, 1920. Serial No. 386,025.

To all whom it may concern:

Be it known that I, HERMAN L. GREVE, a citizen of the United States, and resident of New York city, in the county of Kings and State of New York, have invented certain new and useful Improvements in Cordage Wrappers and Packages, of which the following is a specification.

My invention relates to cord, twine, and small rope and the object of my invention is to provide a package comprising a wrapper to hold a hank of cord or small rope together in place of winding the end of the rope around the middle portion to hold the hank together as has heretofore been the common practice by the rope manufacturers.

A further object is to provide a wrapper that will serve as a tag and with a display surface on which may be printed or embossed the name of the manufacturer, the quality of the goods, address, etc.

A further object is to provide a wrapper that is strong and that can be provided at a very low cost, and that can be detached and a part of the rope used and thereafter again be placed on the hank to hold the remaining coils together until needed for use.

Referring to the drawings which form a part of this specification:

30 Figure 1 is a front elevational view showing the complete package embodying my invention.

Figure 2 is a cross sectional view taken on line 2—2 of Figure 1.

35 Figure 3 is a perspective view of the inner side of the wrapper.

Figure 4 is a view of a modified construction of the wrapper in which two clasps or hooks are used instead of one, as illustrated 40 in Figure 1.

A indicates a hank of small clothes line with the looped ends cut off to save space in illustrating. B indicates a wrapper made of thin, strong, flexible material such as 45 tough paper or tinned sheet iron. In the present drawings the material is illustrated as tough paper or card-board. This paper is preferably cut in a substantially rectangular form and is provided with a perforation

50 B' through which the hook C is passed in locking the ends of the wrapper together. The hook C is provided with a forwardly extending projection C' which extends under the body portion of the wrapper when the ends of the wrapper are in locked relation and prevents the disengagement of the

hook C in case the wrapper fits loosely over the rope when a portion of same has been removed as the hook may shift in its position relative to the coupled end of the wrapper without lifting out of engagement therewith, as will be readily understood. The shank C² of the hook C is secured to the end of the wrapper B² by perforating the wrapper at D and passing the shank end of the hook through the perforation and bending it over in the usual manner. To uncouple the ends of the wrapper the hook is forced forward until the inner loop C³ contacts the edge B³ of the perforation B' in which position the end of the loop of the hook C can be raised sufficiently above the plane of the wrapper to permit the hook to be withdrawn and the ends of the wrapper uncoupled. If desired, a second perforation indicated by E 60 65 70 75 80 85 90 95 100 105 110

may be made in the wrapper to more closely bind the rope together after a portion has been removed by coupling therethrough.

By this invention a rope package is provided that provides, in effect, a mailing wrapper, since the address of the consignee and the postage stamp can be placed thereon. The cost of wrapping the hank of rope with the rope end is also saved and, in fact, the cost of the present wrapper is less than the cost of labor in wrapping with the rope end as now so generally done.

Having thus described my invention, I claim as new and desire to secure by Letters Patent of the United States:

1. A package wrapper adapted to encircle a hank of cordage comprising a sheet of strong, flexible material, one end of which is provided with a perforation and the opposite end having a sinuous hook adapted to be passed through said perforation to couple the ends of the wrapper together.

2. A package wrapper adapted to encircle a hank of cordage comprising a sheet of strong flexible material, each end of which is provided with a perforation, a hook adapted to be inserted in one of the perforations, said hook having a flat portion adapted to lie on the inner side of the wrapper, a shank connected with the afore-mentioned portion and adapted to lie on the outer side of the wrapper, an inner loop united to the shank by a curved portion adapted to pass through the perforation in the other end of the wrapper when the same is rolled up, said inner loop having a flat side lying against the inner side of the wrap-

per and an extended projection adapted to project under the body of the wrapper beyond said perforation.

3. A package wrapper having perforations near each end, a hook adapted to couple the ends of the wrapper when rolled up, said hook having an end adapted to lie between the inner surface of one end of the wrapper and the outer surface of the other end, thence passing through one perforation and outside of the outer surface of the wrapper around the extreme ends of the wrapper, thence adjacent the inner surface of the

wrapper and having a projection extending in the opposite direction under the body of the wrapper beyond said ends thereof to keep the ends of the wrapper coupled together.

Signed at New York city in the county of Kings and State of New York, this 1st day 20 of June, A. D. 1920.

HERMAN L. GREVE.
